US00D847226S

(12) **United States Design Patent** (10) **Patent No.:** **US D847,226 S**
(45) **Date of Patent:** **** Apr. 30, 2019**

(54) **VACUUM SEALER**

(71) Applicant: **Sunbeam Products, Inc.**, Boca Raton, FL (US)

(72) Inventors: **David Owens**, Boynton Beach, FL (US); **Adam Day**, Boynton Beach, FL (US); **Jason Harris**, Boca Raton, FL (US)

(73) Assignee: **Sunbeam Products, Inc.**, Boca Raton, FL (US)

(**) Term: **15 Years**

(21) Appl. No.: **29/607,834**

(22) Filed: **Jun. 16, 2017**

(51) LOC (11) Cl. **15-03**

(52) U.S. Cl. **D15/134**

(57) **CLAIM**

The ornamental design for the vacuum sealer, as shown and described.

DESCRIPTION

FIG. 1 is a front perspective view of the vacuum sealer; FIG. 2 is a front view thereof; FIG. 3 is a rear view thereof; FIG. 4 is left side view thereof; FIG. 5 is a right side view thereof; and, FIG. 6 is a top view thereof.

The broken lines depict portions of the vacuum sealer that form no part of the claimed design.
